(57) CLAIM

The ornamental design for a hood with patterned lining, as shown and described.

DESCRIPTION

FIG. 1 is a front-right perspective view of a hood with patterned lining showing the novel design;

FIG. 2 is a front-left perspective view of the hood with patterned lining, showing the novel design;

FIG. 3 is a front-center view of the hood with patterned lining, showing the novel design; and,

FIG. 4 is an enlarged view of a section of FIG. 3, illustrating the shemagh pattern on the hood with patterned lining.

The broken line showing of the garment is for the purpose of illustrating environment and forms no part of the claimed design.
